UNITED STATES PATENT OFFICE.

ALFREDO ZECCHINI AND INNOCENTE PANZA, OF TURIN, ITALY.

COMBINED FOOT SUPPORT AND HEATER FOR VEHICLES.

1,361,954.

Specification of Letters Patent. Patented Dec. 14, 1920.

Application filed February 24, 1920. Serial No. 260,680.

To all whom it may concern:

Be it known that we, ALFREDO ZECCHINI and INNOCENTE PANZA, subjects of the King of Italy, and residents of Turin, Italy, 5 have invented certain new and useful Improvements in Combined Foot Supports and Heaters for Vehicles, of which the following is a specification.

This invention relates to foot heaters 10 adapted to be used in motor cars and other vehicles of any kind and has for its object a type of said device which may be used both as electric foot heater and as foot support without heating, the device according 15 to this invention being adapted to be swung out of operative position so as to require a very reduced space in the vehicle when the same device is not in use.

The annexed drawings show by way of 20 example an embodiment of this invention and Figure 1 is a diagrammatic view of the device; Fig. 2 is an end view of the same in operative position; Fig. 3 is the transverse section of the foot supporting plate; Fig. 4 is the front view of the same with its 25 supporting means in section to show electric connections and details of mounting; Fig. 5 is a fragmentary view showing a modified construction of said mounting.

As shown by Fig. 1 the device comprises 30 essentially two supports, each consisting of two metal bars 1 and 2 and a foot supporting plate 3 journaled in said supports. Said supports are intended to be mounted on the 35 vehicle floor and said plate 3 is provided with heating means, as an electric resistance 18, adapted to be inserted in the circuit of a source of electric current; in the embodiment illustrated said source is assumed to 40 be a battery 4 but it is to be understood that any other source or generator mounted on the vehicle for any purpose may be used.

The foot supporting plate consists of a 45 metal plate 5 (see Figs. 3 and 4) having upturned edges 6 forming therein a hollow space 7 in which is located a heating resistance 18 this latter being preferably wrapped in a cloth or felt layer 19 filling in said hollow space 7; said plate is pivoted 50 on a longitudinal spindle 8 the ends of which are adapted to seat into bearings or collars 1' and 2' provided in adjacent ends of bars 1 and 2, as hereinafter described. One of the ends of said spindle 8 is provided 55 with an enlarged head 9 and the opposite end is screwthreaded to receive a nut 10

bearing against an insulating washer 20 inserted between said nut and collar 2' of bar 2; said nut 10 allows of clamping plate 3 between said supports in any desired position. As shown in the drawing insulating sleeves 23 are inserted between spindle 8 and collars 1', 2' and hubs 3' of plate 3, head 9 of said spindle on the contrary contacting with collar 2' of bar 2.

The device is conveniently mounted on the vehicle in the manner shown by Fig. 2; say a bar 1 of each support is pivoted by one end to a piece 14 secured to the vehicle floor by means of bolts 15, while the collar 1' provided at the opposite end of said bar 1 encircles one of the ends of spindle 8 and associate sleeve 23; the other bar 2 of each support is likely pivoted by means of collar 2' on the sleeve 23 and spindle 8 and has its opposite end free, this free end being adapted to bear against the vehicle floor.

By this mounting it is possible to impart to foot supporting plate 3 any required position as, by unscrewing nut 10, bars 1 may 80 be rotated around their pivots in pieces 14 and the free ends of bars 2 may be moved on the vehicle floor, plate 3 being at the same time allowed of swinging around spindle 8 to take up any desired inclination; 85 after said parts have been carried in the desired position the same may be clamped or locked by screwing up nut 10.

The device may also be carried close 90 against the vehicle floor, to reduce the space occupied by the same when out of use, by arranging bars 2 parallel with and adjacent to bars 1 and by carrying these bars and plates 3 to lie close to said floor.

This invention provides further means 95 for breaking the electric circuit feeding heating means when said plate 3 is rotated to take its inoperative position and the position in which the same acts as foot supporting means without heating.

In the construction shown by Fig. 4 the collar 1' of one of bars 1 providing the support for spindle 8 is lined with an insulating sleeve 11 which has a flange 11' located between said collar 1' and the adjacent surface of hub 3' of plate 3. Said flange is provided with a contacting plug 12 embedded therein and one end of electric resistance 18 located in said plate 3 leads to a contacting plug 13 insulated from said hub and adapted to come in contact with plug 12. Said sleeve 11 is further provided with a flange

11" inserted between collars 1' and 2' of bars 1 and 2 to insulate these pieces from each other.

The ends of said resistance 18 are connected respectively with plug 13 and with spindle 8 and the terminals of battery 4 are connected by means of wires 21 and 22 with each bar 1, said wires leading to bolts 15 securing said pieces 14 to the vehicle floor; said pieces 14 and bolts 15, or at least one of said pieces and associate bolts, are suitably insulated from the vehicle floor in the case this latter should not be of insulating material.

Then when said plate 3 is in position shown by Fig. 4, that is when plug 13 contacts with plug 12, the circuit of battery 4 is closed through heating resistance 18 as follows: battery 4, wire 21 leading to bar 1, plug 12 contacting with said bar, plug 13 contacting with plug 12, resistance 18, spindle 8, head 9, bars 2 and 1 adjacent to this head and wire 22 leading to opposite pole of battery 4.

By swinging plate 3 around its bearings by the described operation of nut 10 so as to carry it in its inoperative position or in a position in which the same acts as foot support without heat development, the resistance 18 is disconnected from battery 4, as by the rotation of plate 3 the plug 13 of the same is carried out of contact with plug 12, said plug 13 contacting with insulated flange 11.

Fig. 5 shows a modified construction of said circuit controlling means. In said construction plate 3 is mounted to rotate, in the above described manner, in supports provided by collars 1' and 2' of bars 1 and 2, and the same is provided with a plug 13 embedded in an insulating washer 24 and connected with one end of resistance 18, said plug being adapted to contact with plug 12 embedded in a washer 16 of insulating material; said plug 12 contacts with bar 1 to which leads one of the wires connected with the battery terminals. The collar 1' of bar 1 is provided with a recess in which is located a spring button 17 acting against insulating washer 16 to remove the same and plate 3 from collar 1'.

By this construction the resistance 18 is inserted into circuit of battery 4 by screwing up nut 10 to clamp plate 3 in proper position and said circuit may be broken by merely unscrewing nut 10 to allow spring button 17 to push washer 16 and plug 12 away from collar 1'; further plate 3 may be arranged in any required position by rotating it around its axis as above described.

In any case one of said contacting plugs 12 and 13 may have a larger circumferential extension than other one to close the circuit of electric resistance 18 within proper ranges of angular displacement of said plate

for the purpose of allowing adjustment of the same in a comfortable position; the same result may also be obtained by arranging the member carrying plug 12 to rotate with regard to collar 1' of bar 1 so as to enable 70 of locating it in the proper position.

Further instead of providing an insulating member having a contacting plug between the collar of bar connected with one of battery terminals and the plate hub to 75 which leads the resistance, said collar may be provided with recesses or cut-out portions to break the circuit when said plate is carried in given positions.

The foot supporting plate may have any 80 required shape and size and the same may be made of any desired material being only essential that said plate is provided with resistances adapted to develop heat when inserted in the circuit of an electric source, 85 said resistances having one end leading to a conducting member permanently connected with one terminal of said source while other end of said resistance contacts with another member and with the source terminal connected therewith when said plate is carried in its operative position.

This invention provides a device which may be used both as foot-heater and as foot-support, the circuit of electric heating means 95 being adapted to be closed in an automatic manner when said plate is carried into foot-heating position or is clamped in the required position, while said circuit is cut out in other positions of said plate.

What we claim as our invention and desire to secure by United States Letters Patent is:—

1. A combined foot-support and heater for vehicles comprising foot supporting means, means for carrying said supporting means, said supporting means being adjustably connected with said carrying means and these carrying means being adjustably mounted on the vehicle floor, means for clamping said means in the required position, heating means in said foot supporting means said heating means being intended to be inserted in an electric circuit, and coöperating means in said foot supporting means 110 and carrying means to close and break said circuit.

2. A combined foot-support and heater for vehicles comprising foot supporting means, means for carrying said supporting 120 means, said supporting means being adjustably connected with said carrying means and these carrying means being adjustably mounted on the vehicle floor, means for clamping said means in the required position, heating means in said foot supporting means said heating means being intended to be inserted in an electric circuit, and coöperating means in said foot supporting means 125 and carrying means to close said circuit 130

when said foot supporting means are located in a position and to break the same circuit when said supporting means are located in other positions.

- 5 3. A combined foot-support and heater for vehicles comprising foot supporting means, means for carrying said supporting means, said supporting means being adjustably connected with said carrying means 10 and these carrying means being adjustably mounted on the vehicle floor, means for clamping said means in the required position, heating means in said foot supporting means said heating means being intended to 15 be inserted in an electric circuit and coöperating means in said foot supporting means and carrying means to close said circuit on said means being locked in the required position by said clamping means.
- 20 4. A combined foot support and heater for vehicles comprising a foot supporting plate, bars adjustably mounted on the vehicle floor, said plate and bars having co-operating parts for pivotally connecting the 25 same together, means for clamping said parts in the required position, heating means in said plate said means being adapted to be inserted in an electric circuit, and coöperating means in said plate and bars to close 30 and break said circuit.

5. A combined foot support and heater for vehicles comprising a foot supporting plate, bars adjustably mounted on the vehicle floor, said plate and bars having co-operating parts for pivotally connecting the same together, means for clamping said parts in the required position, said plate providing a space, heating means in said space, said means being adapted to be inserted in an electric circuit, and coöperating means in said plate and bars to close and break said circuit.

6. A combined foot support and heater for vehicles comprising a foot supporting plate, bars having one end pivoted on the vehicle floor, means connecting pivotally the opposite ends of said bars with said plate, bars journaled at one end on said connecting means and having their opposite 50 end adapted to move on and rest against the vehicle floor, means for clamping said parts in the required position, heating means in said plate adapted to be inserted in an electric circuit and coöperating means on said 55 plate and bars to close and break said circuit.

7. A combined foot support and heater for vehicles comprising a foot supporting plate having hubs, a spindle passing through said hubs, bars having one end pivoted on said spindle and opposite end pivoted on the vehicle floor, bars journaled at one end on said spindle and having their opposite end adapted to move on and rest against 65 the vehicle floor, a screwthreaded member

on said spindle for clamping together said plate and bars in the required position, heating means in said plate adapted to be inserted in an electric circuit, and coöperating means in said hubs and bars to close 70 and break said circuit.

8. A combined foot support and heater for vehicles comprising a foot supporting plate, bars adjustably mounted on the vehicle floor, means for pivotally connecting 75 together said bars and plate, means for clamping said plate and bars in the required position, an electric resistance in said plate, means connecting one end of said resistance with one terminal of an electric source, a 80 contacting member on said plate, the other end of said resistance leading to said contacting member, a contacting member on one of said bars this contacting member being connected with other terminal of said source, said contacting members being able of contacting with each other for inserting 85 said resistance in said circuit when said plate is carried in proper position.

9. A combined foot support and heater for 90 vehicles comprising a foot supporting plate, bars adjustably mounted on the vehicle floor, means for pivotally connecting together said bars and plate, means for clamping said plate and bars in the required 95 position, an electric resistance in said plate, means for connecting one end of said resistance with one terminal of an electric source, a contacting member on said plate, the other end of said resistance leading to 100 said contacting member, a contacting member on one of said bars this contacting member being connected with other terminal of said source, said contacting members being able of contacting with each other for inserting 105 said resistance in said circuit when said plate and bars are clamped together by said clamping means.

10. A combined foot support and heater for vehicles comprising a foot supporting 110 plate having hubs, a spindle passing through said hubs, two bars each having one end pivoted on said spindle and opposite end connected with the vehicle floor, adjustable means for supporting said spindle and plate, 115 means on said spindle for clamping together said parts in the required positions, an electric resistance in said plate having one end connected with one of said hubs and bars, a contacting member on other hub, the opposite end of said resistance leading to said member, a sleeve insulating other bar from said spindle and adjacent plate hub and a conducting part in said sleeve adapted to connect electrically said bar and contacting 125 member when said plate is carried in proper position, each of said bars being connected with one terminal of an electric source.

11. A combined foot support and heater for vehicles comprising a foot supporting 130

plate having hubs, a spindle passing through said hubs, two bars each having one end pivoted on said spindle and opposite end connected with the vehicle floor, adjustable means for supporting said spindle and plate, an electric resistance in said plate having one end connected with one of said hubs and bars, a contacting member on other hub, the opposite end of said resistance leading to said member, an intermediate insulating member between this hub and adjacent bar, a conducting part in said insulating member contacting with said contacting member, a resilient member in said bar act-

ing to hold said insulating member and conducting part thereof removed from said bar and means on said spindle for clamping together said parts in the desired position and for carrying said conducting part in contact with said bar against action of said resilient member, each of said bars being connected with one terminal of an electric source.

Signed at Turin, Italy, this 20th day of January, 1920.

ALFREDO ZECCHINI.
